WIRE STRIPPING APPARATUS

Louis M. Carpenter and Rudolph G. Roesch,
Syracuse, N. Y., assignors to The Eraser Company, Inc., Syracuse, N. Y., a corporation of New York

Application November 6, 1945, Serial No. 626,998

14 Claims. (Cl. 15—21)

1

The invention relates to an improved means for removing coatings and coverings from wire and, more particularly, to an improved means for and method of removing insulating coverings, and insulating coating films such as so-called enamel films, from electrical wire, including especially wire of small gage generally known as resistance wire or magnet wire. Coating films used vary widely as to hardness and toughness and as to the tenacity with which they adhere to the wire. Such wires with insulating coverings, or with adherent insulating coatings or films, are widely used in radio and radar equipment, magnet coils, rheostats, potentiometers, electric controls, measuring instruments, etc.

Electrical wire of small gage with an insulating covering or coating has long been used and, in recent years, the demand for such insulated wire has vastly increased along with a demand for wire of smaller and smaller gage. In using such wire, it is necessary to remove the insulation from portions of the coated wire in order to make electrical connections with wire terminals, etc. Removal of the insulation from wires, and especially from wires of small gage, has long presented a problem the successful solution of which has increased in difficulty as the demand has arisen for wires of smaller and smaller gage until even the insulated wires are of such small diameter that they can hardly be seen with the naked eye. Wire of 0.0009 inch diameter uninsulated, having applied thereto an insulating covering or coating 0.00015 inch thick, giving a total coated wire diameter of 0.0012 inch, has not been uncommon for some time past, particularly where the wire is provided with an adherent insulating coating. The smaller the diameter of the insulated wire, the more difficult it has been to strip the insulation therefrom.

It has been proposed to remove the insulation from portions of such insulated wire by various means and methods, as by manual scraping or abrading, by abrading by machine (as, for example, by the periphery of a rotating wire brush), by burning, by dipping in hot solder, by the use of chemicals, etc., but all such known means have met with little practical success, particularly with wires 0.003 inch or less in diameter, due to some one or more of such causes as undue cost, undue time and labor required, a substantial reduction in the often critical diameter of the metal wire which impairs or destroys its usefulness, mechanical or chemical

injury to the stripped portion of the wire, rupture of the wire by burning or by stripping tools, failure to clean all of the coating from the stripped portion of the wire, hazards to workers cleaning the wire, and others. Frequently, the injuries to the wire do not result in wire rupture until after the device in which the wire is employed has been manufactured and put into use. Other such injuries result in great waste of wire due to wire rupture during stripping the wire or during manufacture of articles in which the wire is used. Production of articles including such wire as an element thereof has been excessively slow due to time required to strip wire and to the high percentage of stripped wire rejected as unfit for use. Much consideration has long been given without success to ways and means of avoiding the hazards to operatives in stripping the wire, the great economic waste existent in manufacture of articles requiring such wire, and the serious consequences resulting from wire failure in use of such manufactured articles.

The general purpose of the present invention is to provide an improved means for rapidly, safely and economically stripping or removing insulating coverings and coatings cleanly and entirely from a desired length of insulated wire, including particularly insulated wire of a total diameter of 0.003 inch, or less, without injuriously affecting or weakening the metal wire or substantially reducing the diameter of the metal wire.

A further purpose of the invention is to provide an improved apparatus whereby insulation is stripped by mechanical means from such wire cleanly and with great rapidity without adversely affecting the metal wire and with little or no liability of injurious effects on the operative.

A further purpose of the invention is to provide a safe, simple, inexpensive and effective apparatus in which the insulation is stripped or abraded from such wires by a novel rotating brush with brushing elements, bristles, or filaments of which extend axially of the brush to an annular working end face of the brush and are glass fibers or filaments of the kind known as continuous fibers or filaments as distinguished from the relatively short glass fibers known as staple fibers.

A further purpose of the invention is to provide a platen means so constructed and so associated with such a brush as is above described as to enable the brush to act with great effi-

ciency on an insulated wire in a manner to obtain the ends desired.

Other purposes and advantages of the invention will appear from the following description of those illustrative embodiments thereof shown in the accompanying drawings.

In the drawings,

Figure 1 is a perspective view of a wire stripping machine constructed according to the invention;

Figure 2 is an exploded detail perspective view illustrating certain parts of the machine;

Figure 3 is a fragmentary vertical sectional view of the machine taken on the same plane as Figure 5;

Figure 4 is a detail perspective view showing the machine equipped with a modified form of platen or counter-pressure plate;

Figure 5 is a detail sectional view on line 5—5 of Figure 6;

Figure 6 is a detail end view of parts of the machine illustrating also how a wire is introduced for stripping;

Figures 7 and 8 are detail views similar respectively to Figures 5 and 6 but illustrating the machine equipped with the modified platen or counter-pressure plate shown in Figure 4;

Figure 9 is a diagrammatic top plan or top edge view illustrating more clearly certain details common to both forms of platen or pressure plate; and

Figure 10 is a detail horizontal sectional view taken on the horizontal plane in which lies the axis of adjusting screw 37.

The improved machine has a rigid framework 10 adapted to be seated upon a table or work bench. A horizontal shaft 11 is journaled in suitable bearings in framework 10 and has fixed thereon at one end thereof a three-step stepped pulley 12. An electric motor 13 is mounted on the framework with the motor shaft 14 parallel to shaft 11. A three-step stepped pulley 15 is fixed on one end of motor shaft 14 opposite pulley 12 and is connected with pulley 12 by a drive belt 16, the pulleys being reversely stepped relatively to each other, as shown, so as to provide in known manner for three changes of speed of drive of shaft 11 by motor 13. Current is supplied to and cut off from the motor through the medium of a suitable electric switch having an operating handle 17 readily accessible to a user of the machine. Mounted on shaft 11 to rotate therewith, and located at the opposite end of said shaft from pulley 12, is a wire stripping brush or tool designated generally by the reference numeral 18.

The brush 18 is of novel construction and is mounted on shaft 11 in a novel manner as now will be described. The brush shown comprises a cylindrical body or band 19 of closely compacted fiber glass filaments which constitute the brushing elements or bristles of the brush. These filaments are flexible and abrasive and are of the kind known as continuous fibers and all extend longitudinally of and parallel to, or substantially so, the axis of the band of filaments. Preferably, the filaments of the band 19 are flexibly bonded or cemented to each other throughout the body of said band by an elastic cement binder. At its inner end, the flexible band 19 of bonded glass filaments is bound on the exterior of a narrow annular metal ferrule or ring 20 having at one end thereof an outwardly extending flange 20a abutted by the inner end of the band of filaments. Each filament extends from end to end of the band of filaments and said band of filaments pro-

jects from the ferrule 20 throughout the major portion of the length of the band and is bound at the inner end of the band on the ferrule 20—20a by means of a wire 21 wrapped helically about the exterior of the band at the inner end of the band with the ends of the wire secured in any suitable manner as, for example, by twisting or tying the wire ends together. The ferrule 20—20a, the band of filaments 19, and the band-binding wire 21 constitute a replaceable and axially adjustable unit or "re-fill" unit of the brush 18, as hereinafter pointed out.

An internally threaded collar 22, having a knurled periphery, is provided with a reduced 15 annular portion 22a to receive the flanged ferrule 20—20a, the length of portion 22a corresponding to that of the ferrule. Collar 22 is screwed on an externally threaded intermediate portion of a sleeve 23 for adjustment along the sleeve. 20 Sleeve 23 closely embraces shaft 11 and is formed at its outer end with an enlarged annular head 23a of greater internal diameter than the diameter of the main shaft-embracing bore of the sleeve. The external diameter of the head 23a 25 corresponds with that of ferrule 20, and this head serves as a rigid internal support for the band of brushing elements of filaments. The outer or working end of the band of brushing elements projects slightly beyond the outer end of the head 23a 30 of sleeve 23 in the assembled condition of the brush and machine, the extent of this projection or protrusion preferably being about $\frac{1}{16}$ to $\frac{3}{32}$ inch. The inner end of sleeve 23 is notched at 35 24 at two diametrically opposed points to closely embrace the protruding ends of a pin 25 driven through a diametrical bore 26 in shaft 11 to thereby provide a positive driving connection between shaft 11 and brush 18.

The brush supporting end of shaft 11 is formed 40 with a reduced and externally threaded terminal portion 11a to receive a clamping washer 27 and clamping nut 28 which releasably hold the sleeve 23—23a on shaft 11 with the inner end of the sleeve abutting a collar 11b fixed on the shaft. 45 The band of brushing elements is clamped tightly to the enlarged head 23a of sleeve 23 by a divided metallic clamping band 29 of known form, the three sections of which are connected by nut and bolt band contracting means 30 in known 50 manner to releasably but tightly grip the band 19 to the periphery of annular head 23a to rotate with sleeve 23 and shaft 11. The outer edge of band 29 is preferably in the same plane as the outer end of head 23a, and the outer end of 55 the band of filaments 19 projects slightly beyond the clamping band 29, preferably $\frac{1}{16}$ and $\frac{3}{32}$ inch. The band of filaments may be advanced beyond the outer end of head 23a, as the filaments wear away in use, by screwing collar 22—22a toward 60 head 23a of sleeve 23. It will be observed that the brushing elements or filaments of brush 18 project at their working ends only a very short distance ($\frac{1}{16}$ to $\frac{3}{32}$ inch, preferably) outward from between head 23a and clamping band 29, so that 65 only a very short length of each filament at the working end of the brush is flexible during brushing action. The threaded terminal portion 11a of shaft 11, and also the washer 27 and nut 28, are housed within head 23a which projects outward beyond the nut and the end of shaft 11, as shown.

The tool or brush, constructed and mounted as hereinbefore described, has an annular working end face located in a vertical plane to which extends all, or substantially all, of the brushing

elements or filaments of the hollow cylindrical band 19 of filaments. Opposed to the working end face of this brush is a small and substantially non-rotative flat platen or counter-pressure plate which is so supported that it is capable of limited universal tilting movement about an axis parallel to the brush axis and may move against yielding resistance away from the working end face of the brush. Two forms of platens, namely platens 31 and 32, are shown in the drawings, each platen being a rigid rectangular plate and having rigid therewith a pendent arm which is engaged with a part of the machine to prevent any substantial rotation of the platen. Each platen proper, apart from its pendent arm, is of such size and shape that it extends across a limited arc of the end face of the annular band of brushing elements of the brush, said arc not exceeding 180 degrees and preferably being of about 60 degrees. Either form of platen may be used, and the machine shown is provided with means for supporting each form of platen. In Figures 1, 3, 5, and 6, one form of platen is shown mounted in the machine, and in Figures 4, 7 and 8, another form of platen is shown mounted in the machine. Figure 9 shows on an enlarged scale features of construction common to both forms of platen.

The platen mounting means now will be described after which will be described the construction of each of the two alternatively usable platens 31 and 32 and the manner in which each platen is supported by the platen mounting means.

Extending across the vertical plane in which lies the common axes of shaft 11 and brush 18 is a horizontal arm 33 which is journaled at one end thereof on a vertical pivot 34. Pivot 34 is fixed to framework 10 at one side of said vertical plane and said arm 33 is located at a lower level than the brush 18 and is partly overhung by the outer or working end of the brush. At the opposite side of said plane the other end of said arm is formed with a yoke 35 in which is journaled the ends of a short vertical shaft or pintle 36. A thumb screw 37 has a shank extending through a horizontal bore in shaft 36, said shank having a screw-threaded terminal portion 37a variably screwable into a horizontal and screw-threaded bore in a vertical post or stud 38 fixed to framework 10, said bore in post 38 extending parallel to, or substantially parallel to, shaft 11. The shank of screw 37, which is not threaded where it passes through shaft 36, is enlarged adjacent the head of screw 37 to provide a shoulder 37b which abuts shaft 36. An expansion spring 39 is coiled about the shank of the thumb screw and abuts shaft 36 and post 38 to constantly urge the adjacent end of arm 33 away from post 38 as far as permitted by the threaded adjustment of the screw in post 38. The threads of the screw 37 and of the bore in the post 38 are of fine or micrometric pitch. Micrometric swinging adjustment of arm 33 may be made by turning the thumb screw, the parts being so constructed and arranged that the short maximum range of swinging adjustment of the arm carries the axis of shaft 36 equal distances to opposite sides of a vertical plane normal to the vertical plane in which lies the common axes of shaft 11 and brush 18 and passing through pivot 34.

In, or substantially in, the vertical plane of the common axes of shaft 11 and brush 18 is an upstanding post or bar 40 which is of non-circular cross-section and is rigidly held at its lower end

to arm 33 for adjustment of post 40 toward and from the working end of the brush substantially in said vertical plane by adjustment of arm 33 through the medium of thumb screw 37. Arm 33 has a post-receiving bore of substantially the same cross-section as the post as hereinafter described. The post 40 extends upward from arm 33 at least substantially entirely past the outer or working end face of brush 18, as shown. At the side thereof farthest from brush 18, the post 40 is provided with a medial longitudinal groove 41 extending throughout the length of the post, and said post has a medial slot 42 extending across its upper end, said groove and slot connecting with each other and lying in, or substantially in, the vertical plane of the common axes of shaft 11 and brush 18 in all adjusted positions of arm 33.

To directly support the platen 31, or the platen 32, the machine is provided with a platen support or hanger which is resiliently flexible. This hanger comprises a piece of resilient metal wire having a long leg 43 seated loosely in groove 41 in post 40, and also having a short horizontal leg 44 extending from the upper end of leg 43 loosely through slot 42 in post 40 beyond the inner edge of post 40 and toward brush 18, said leg 44 extending parallel, or substantially so, to the brush axis. The platen hanger 43-44 is adjustable up and down relatively to post 40 and is clamped in adjusted position by a thumb screw 45 which is threaded through arm 33 to abut the long leg 43 of the hanger adjacent the lower end of the hanger and post. The leg 43 of the hanger is preferably slightly shorter than the distance between the lower end of slot 42 and the lower end of post 40.

For convenience in manufacture, the arm 33 is provided with a passage of substantially the same cross-section as post 40 to receive the lower ends of post 40 and of hanger 43-44, the post being, as shown, of substantially rectangular cross-section and the arm and post having flat lower faces adapted to wipe over an underlying flat surface of the main frame when the arm is adjusted. The depth of slot 42 in post 40 is such that the platen hanger may be adjusted to position the tip of the conically tapered end 44a of leg 44 of the hanger opposite the end face of the annular band of brushing elements above the brush axis (i. e. between prolongations of the inner and outer peripheries of band 19 and above said axis), or at a point which is above the brush axis but inside a prolongation of the inner periphery of band 19 of brushing elements. When the thumb screw 45 is screwed inward, it serves to lock the post 40 to arm 33 and also to lock hanger 43-44 in its adjusted relation to the post 40. The post 40 could, of course, be made integral with arm 33, if desired.

To vary the force necessary to flex the upper end of the hanger 43-44 away from the working end face of brush 18, there is provided a collar or sleeve 46 which embraces, and is slidable up and down relatively to, the post 40 and hanger leg 43, and which has threaded therethrough a set screw 47 adapted to bind leg 43 to post 40 at varying points along the length of said hanger leg. To prevent frictional binding of the hanger 43-44 in groove 41 and slot 42, the groove and slot are made wide enough to provide slight side clearance for the hanger, as indicated particularly in Figures 6 and 8.

Platen 31 has a straight pendent arm 49 rigid therewith and lying in the same plane as the

platens proper, said arm having a longitudinal slot 50 in its lower end portion through which extends, when said platen is mounted on the hanger, the horizontal crossbar of a wire yoke 51. The yoke 51 is rigidly held to arm 33 with its crossbar parallel to shaft 11 and lying in, or substantially in, the vertical plane in which lies the common axes of shaft 11 and brush 18, said crossbar extending partly under, and also partly outward beyond, brush 18, as shown. Slot 50 is slightly wider than the yoke crossbar, and the crossbar extends through slot 50 intermediate the ends of the slot, to prevent binding of the arm 49 on the yoke when the platen is tilted on the conical end 44a of the hanger. The connection between the arm 49 and yoke 51 prevents any substantial rotation of the platen 31 when the brush 18 is rotated.

The pendent arm 52 of platen 32 is shorter than arm 49 of platen 31 and is inclined downward and outward for engagement of the lower end of said arm 52 in a longitudinal slot 53 in post 40 when the platen 32 is mounted on the hanger 43-44. Slot 53 extends medially of post 40 and is slightly wider than the arm 52 and is of sufficient depth to permit limited facewise tilting of the platen 32 into and out of a vertical plane normal to the vertical plane in which lies the axis of the shaft 11. The above described arrangement permits limited universal tilting of platen 32 on the conical hanger end 44a without binding of platen arm 52 on the post 40, and prevents also any substantial rotation of the platen when the brush is rotated.

The pendent arm of each platen is a rigid arm which is connected with the platen midway the vertical or side edges of the platen and preferably is formed integrally with the platen, as shown. Each platen has an accurately ground planar inner or working or wire-engaging surface or face which is connected with the outer face of the platen at the two vertical or side edges of the platen by two flaring side edge surfaces 54, best shown in Figure 9, which gradually merge with the planar inner or working surface of the platen. Preferably the flaring side edge surfaces of the respective platens are curvilinear surfaces of large radius.

The dimensions of the alternatively usable platens 31 and 32 are such that, when either platen is mounted on the hanger, the annular working end face of the brush is always opposed to the planar working surface of the platen in a single fixed arcuate zone which does not exceed 180 degrees of said brush face. This is an important feature. In the constructions shown, this zone is located above the horizontal level of the brush axis and crosses the platen from one vertical side edge to the other of the platen between and short of the upper and lower edges of the platen.

In using platen 31, the platen hanger is preferably so adjusted that the conical tip 44a of the hanger is directly over, or substantially directly over, the brush axis with said tip slightly below a prolongation of the inner periphery of the band of brushing elements 19, as shown in Figures 1, 3, 5, and 6. In using platen 32, the platen hanger is preferably so adjusted that said hanger arm tip 44a is opposed directly to the annular working end face of said band of brushing elements and is directly over, or substantially directly over, the brush axis, as shown in Figures 4, 7 and 8. When either platen is mounted in the machine, the arm 33 is so adjusted by screw 37 that

the planar working surface of the platen either only very lightly contacts the working end face of the brush without any flexure of the resilient wire hanger 43-44, or else so that there is a minute normal clearance between the brush and platen not exceeding the diameter of the metal core of the coated wire to be stripped. Such adjustments of the platen will insure proper insulation stripping action and also prevent undue wear of both the brush and the platen.

When the brushing elements of the brush 18 are worn away as far as practicable, the ferrule 20-20a and the band 19 of brushing elements bound thereon by wire 21, are removed and a refill comprises a new ferrule and a new band of brushing elements bound thereon by a new binding wire 21 is incorporated in the brush.

When the band of brushing elements is to be adjusted to compensate for wear, by screwing the ring 22-22a toward head 23a of the brush core or sleeve 23, the clamping band 29-30 should be loosened so that the "re-fill" unit can move axially relatively to the sleeve 23-23a.

Mode of stripping a wire

In the drawings, the brush is shown as being continuously rotatively driven by the motor in counter-clockwise direction as indicated by the arrows in Figures 1, 4 and 6, during use of the machine. With this direction of brush rotation, the mode of stripping the insulation film from a desired length of an insulated wire is as now will be described.

The insulated wire 55 (Figure 6) is grasped between the thumb and index finger of a hand of an operative and is introduced laterally thereof between the brush and platen as indicated in full lines in Figure 6, and the operative's hand then is moved directly, or substantially directly, downward, as indicated in dotted lines in Figure 6, this downward hand motion being continued until the wire is carried below the platen proper, i. e. below the rectangular plate 31 or plate 32, whichever one is mounted in the machine. As the wire is introduced, adjacent the point of finger grip thereon, between the end face of the brush and the adjacent flared vertical side edge surface 54 of the platen plate, it will be gripped with progressively increasing frictional force between said brush face and platen side edge surface and thereafter carried by the rotating brush between the brush end face and the main or planar working surface or face of the platen adjacent the upper right hand corner (as viewed in Figure 6) of the platen. As the operative's hand moves down and the brush rotates, the wire is drawn on down past the platen by the action thereon of the rotating brush and the brush abrades the insulation from that length of the wire which passes between the planar inner face of the platen and the end face of the brush. In passing between the platen and brush, the wire to the left (as viewed in Figure 6) of the point of finger grip is rolled or twisted through one or more revolutions, the extent of roll or twist progressively increasing to the left of said point of grip.

After a length of the wire has been carried down past the platen proper, it is no longer gripped between the brush and platen and may be withdrawn endwise and the same length thereof again passed down between the platen and brush as above described, if the insulation has not been entirely stripped from said length of wire by the single pass. Preferably, where

more than one pass is required to strip the insulation, the wire is repeatedly passed between the brush and platen by moving the wire gripping hand of the operative alternately down and up to pass said length of the wire down and up between the brush and platen as often as may be necessary to clean the insulation from the wire.

The universally tilttable platen will tilt to facilitate and ease the initial grip of the wire between the brush and platen on each hand stroke, and the platen hanger will resiliently flex away from the brush to permit the wire to be easily drawn by the rotating brush entirely past the platen with very little resistance but with enough resistance to keep the wire lightly pressed by the platen against the brush end face.

The rotary motion of the brush end face past the nonrotating platen carries the wire down past the platen, and also simultaneously rotates, rolls or twists the wire about its axis so that the rotating brush automatically abrasively acts on the wire entirely around the circumference of the wire to abrade the insulation therefrom and also supplies the power to carry the wire laterally thereof in an up and down direction past the platen. The operative merely uses his hand force to start or guide the wire between the platen and brush and need not, and should not, thereafter during a pass of the wire between the platen and brush exert any substantial draft, or pull on the wire either in up or down or endwise direction.

If an end portion of a wire is to be stripped, the wire is introduced as shown in Figure 6 so that the desired end of the wire will pass between the brush and platen. If an intermediate portion of a wire is to be stripped, such intermediate portion is passed between the brush and platen. Where a long length of wire is to be stripped, successive lengths thereof may be stripped by passing such lengths once or more between the brush and platen. The down and up passes, above described, of the wire being stripped obviously will result in the wire being twisted on the down pass and correspondingly untwisted on the up pass, which is advantageous where more than one pass is required to fully clean the insulation from the wire since the wire at the end of each upward pass is restored to its untwisted condition.

The apparatus and method above described are effective to cleanly and entirely strip the insulation from a desired length of wire of the class described without hazard to the operative and without either reducing the metal core of the coated wire, rupturing the wire or producing nicks or cavities in the metal core or wire proper, nor is the wire subject to such injuries as are or may be produced by burning off the insulation, or by removing the insulation by chemical solvents. The brushing unit 19 of the brush comprising the glass filaments and their binding agent is also of such construction and materials that particles thereof and particles of the removed coating do not adhere to the metal wire core but, rather, adhere to each other and fall away from the wire.

Since, even with brushes of the form shown, there is a tendency of the brushing elements to acquire a permanent bend in one direction if the brush is always rotated in one direction, the motor 13 preferably is of the known reversible drive type and the control switch 17 is of the known type, effective to shut off current from said motor or to energize said motor to rotate its shaft 14 in one direction or the other as may

be desired. When the direction of rotation of the brush is in reverse to that indicated in Figure 6, the operative's hand would be positioned and moved at the left of the brush as the latter is shown in Figure 6.

The ideal speed of the rotation of the brush shaft depends upon the nature of the insulating covering or insulating coating to be removed. It has been found that by using the best of three speeds of rotation of the brush, all types of coatings can be stripped to best advantage, and this is the reason why the three-speed pulley and belt drive shown is provided, although change of speed is not essential to the practice of the invention with different types of coating. The variable pressure required to make the platen mount yield is also a desirable feature with different types of coatings or coverings, but this variable pressure yield is not essential nor is any yield of the platen mount essential, although the yield variable, or otherwise, is highly desirable. Where a yielding platen mount such as shown is employed, the pressure should always be very light. The ideal or best R. P. M. and platen yield resistances are determined largely by the nature of the insulation in accordance with known practice in the grinding art wherein the R. P. M. of the tool and pressure of the tool on the work are desirably varied in accordance with the physical characteristics of the material of which the work is formed.

It is not essential that the working face of the platen be above the horizontal level of the brush axis. It is not essential that the brush axis be horizontal. It is not essential, although highly desirable for practical purposes, that the platen be either tilttable or yieldable. It is important that the working face of the brush be in a plane intersecting and normal to the brush axis. The flexible character of the working end face of the brush and the adjacent end portion of the cylindrical body 19 adapt the brush to act efficiently to strip insulation from the wire entirely around the wire. The tilttable and the yieldable mount of the platen are each and both desirable for easy wire introduction, prevention of wire rupture, for good cleaning of the wire (i. e. for insuring continuous contact of a length of wire with a zone of the brush face during passage of the wire through said zone), and for enabling cleaning of wires within a given small range of diameters without adjustment of the platen mount.

Desirably the cylindrical body 19 of flexible and bonded continuous fiber glass filaments employed as a part of the abrading tool or brush may be formed by producing a slab of compacted and bonded fibers with the fibers all running in one direction and from end to end of the slab following in producing this slab the teachings of Roesch United States Patent No. 2,210,432, issued August 6, 1940. While any of the fiber bonding agents mentioned in said patent may be used, it is preferred that an elastic bonding agent such as rubber cement, or the rubber or rubber compound bonding agents (such as "Vultex") mentioned in said patent be employed. After forming the slab, it is severed at intervals, at right angles to the direction of run of the fibers, into lengths corresponding to the desired length of the tool body 19. From these lengths are cut segments of the cylindrical tool body, in which segments substantially all of the fibers extend longitudinally of, and from end to end of, the segments. The required number of segments is assembled to form a cylindrical body, the abutting

11

faces of the segments of which are bonded with some of the fiber bonding material. The cylindrical body is bound on a ferrule 20—20a by a wire 21, and the working end face of the body is ground until it is normal to the axis of the body.

Machines of the kind shown and described have proven particularly successful in removing insulation from wires of even such small diameters as 0.003 inch and less. One such machine used to strip insulated wires of diameters of 0.003 or less inch was operated under the following specific conditions and had the following specific features of construction:

Filament band 19 had an external diameter of 2.25 inches and an internal diameter of 1.75 inches; the fiber glass filaments were of diameters ranging from 0.0006 to 0.0008 inch; and the bonding material for the filaments was a neoprene water dispersion.

The platen measured (exclusive of its pendent arm) 1.00 inch wide and 0.75 inch high. The working face of the platen opposed the working end face of the filament band through an arc of about 60 degrees.

The three-speed drive was arranged to drive the brush at either 900 R. P. M., 1200 R. P. M. or 2000 R. P. M.

In stripping ordinary enamel magnet wire long known in commerce and with diameters of from 0.0008 to 0.004 inch, the platen mounting means was adjusted to permit the platen to yield against minimum or substantially zero resistance so that the platen exerted practically no pressure on the wire. For such ordinary enamel wires having diameters within the range of 0.0008 to 0.0015 inch, the brush was driven at 900 R. P. M., while with such wires having diameters from 0.0015 to 0.004 inch, the brush was driven at 1200 R. P. M.

In stripping magnet wires of diameters of from 0.001 to 0.003 inch, insulated with either "Formex" or "Formvar," the brush was driven at 2000 R. P. M. and the platen mounting means was adjusted to exert a somewhat greater pressure on the wire than the minimum or substantially zero pressure above mentioned, but still to exert only slight pressure.

Although we have thus described our invention in considerable detail in the best forms of which we are aware, in accordance with the patent statutes, it will be evident that various changes and modifications may be made by those skilled in the art without departing from the spirit of our invention. Accordingly, we desire to be limited only by the prior art and the scope of the appended claims.

We claim:

1. An apparatus for the purpose set forth comprising, in combination, a rotatively mounted tool having encircling its axis a cylindrical body of abrasive filaments arranged with the filaments extending longitudinally of the body and forming at one end of the tool an annular abrasive and flexible working end face of the tool normally lying in a plane normal to the tool axis, means for rotating the tool, a platen having a planar working surface opposed to said working end face of the tool through an arc not exceeding 180 degrees, and means to restrain the platen from substantial rotation about the tool axis and to support said platen for the passage of a length of insulated wire laterally of the wire between and in contact with said platen surface and said tool face for stripping of insulation from the wire by said tool face.

12

2. An apparatus, as claimed in claim 1, having means for micrometrically adjusting the platen bodily toward and from the working end face of the tool into and out of contact with the working end face of the tool.

3. An apparatus, as claimed in claim 1, wherein the abrasive filaments of the tool are fiber glass filaments of the continuous type, and wherein said tool includes means engaged with said body of filaments immediately adjacent said working end face of the tool to hold said body of filaments against flexure and to leave free to flex a short end portion of said body which terminates at said face.

4. An apparatus, as claimed in claim 1, wherein the abrasive filaments of the tool are flexibly bonded throughout the cylindrical body of filaments by an elastic cement binder, and said body of filaments is held at its inner and outer surfaces immediately adjacent its working end face against flexure.

5. An apparatus, as claimed in claim 1, having means supporting the platen for limited universal tilting movement thereof relatively to the tool out of a position in which the working face of the platen is parallel to the plane of the working end face of the tool.

6. An apparatus, as claimed in claim 1, having means yieldingly urging the platen facewise toward the working end face of the tool, and means to positively limit such movement of the platen.

7. An apparatus, as claimed in claim 1, wherein the tool includes a rotatively mounted rigid core encircled by said body of filaments, and means for adjusting said body of filaments axially on the core to maintain the working end of said body of filaments projected beyond one end of the core as the body of filaments wears away in use.

8. An apparatus for the purpose described comprising, in combination, a tool mounted for rotation about a fixed axis, said tool having a flexible cylindrical abrasive body which encircles the tool axis and terminates in an annular working end face lying in a plane normal to said axis, the tool further having means gripping said body internally and externally of the body entirely around the body in a zone closely adjacent but spaced from said end face of the body and holding the gripped portion of the body against flexure and leaving said end face and a short length of said body from said face free to flex, means to rotate the tool, a rigid platen having a planar surface adapted to extend over said end face of the tool body through an arc not exceeding 180 degrees, and platen supporting means to hold said platen against rotation with its said surface opposed to said end face of the tool body for passage of a wire laterally thereof between and in contact with said platen surface and tool body end face to strip the wire.

9. An apparatus, as claimed in claim 8, wherein the tool rotating means is adapted to rotate the tool at different selected speeds, and the platen supporting means is constructed to permit the platen to move away from the end face of the tool body against yielding resistance and includes provision for varying said yielding resistance.

10. A rotary abrasive tool, for stripping insulation from insulated electrical wire, comprising a cylindrical body of closely compacted flexible glass filaments substantially all of which ex-

13

tend from end to end of the body substantially longitudinally of the body, a rigid core extending axially into said body and terminating short of one end of said body, said core having a cylindrical peripheral surface supporting said body adjacent said one end of the body, said body having at said one end a working end face lying in a plane normal to the tool axis, and means releasably clamping said body entirely thereabout to said core to rotate with said core with a short cylindrical portion of said body free of said clamping means and core and extending to said end face of the body.

11. A rotary abrasive tool, as claimed in claim 10, wherein the glass filaments are flexibly bonded to each other throughout said body by an elastic cement.

12. In an apparatus for removing an insulating coating from a coated electrical wire, the combination of a platen having a rigid and planar working face for contact with a length of a coated electrical wire from which the coating is to be removed, a coating-removing tool having an annular working end face which is abrasive and universally flexible and normally is disposed in a plane, means to support the tool for rotation about a fixed axis with the working end face of said tool opposed to and crossing said working face of the platen through an arc not exceeding 180 degrees, means to support the platen against substantial movement about the axis of rotation of the tool and in

14

position for lateral passage between and in contact with said tool face and platen face of a length of wire from which coating is to be removed by the tool, and means to rotate the tool about said axis relatively to the platen.

13. An apparatus, as claimed in claim 12, having platen supporting means adjustable to selectively position the platen with its working face in and out of contact with the working face of the tool, said adjustable supporting means supporting the platen for limited universal tilting of the platen relatively to said means.

14. An apparatus, as claimed in claim 12, having platen supporting means yieldingly supporting the platen for movement away from the working face of the tool, and means for at will varying the resistance to such yielding movement of the platen.
